REFRIGERANT DRIER

Evan Jones, Evanston, Ill., assignor to Henry Valve Company, Incorporated, Melrose Park, Ill., a corporation of Illinois

Application October 3, 1956, Serial No. 613,782

12 Claims. (Cl. 210—291)

The present invention is directed to an improved form of refrigerant drier which utilizes a molded type of dehydrant block element mounted within a casing through which refrigerant is passed for the purpose of filtering and dehydrating the same. More specifically, the present invention is directed to different forms of refrigerant driers each utilizing an improved type of dehydrant block which is received and positioned within the casing of the drier assembly itself or within the casing of a cartridge type element insertable within a drier assembly in a new and improved manner which results in a simplified construction of efficient functioning.

It is an object of the present invention to provide an improved form of refrigerant drier assembly and/or cartridge of uncomplicated construction which includes the provision of a molded dehydrant block inserted within a casing and being held at one end thereof by suitable means fixed relative to the casing, the casing having additionally received therein discrete dehydrant material which substantially surrounds the block and acts to position and support the same within the casing in spaced relation with respect to the inner surface thereof.

A further object is to provide an improved form of refrigerant drier assembly and/or cartridge insertable within a drier assembly of uncomplicated construction which utilize a relatively small number of parts to provide efficient refrigerant drying and filtering action, the drier assembly and/or cartridge being readily and economically manufactured and being of low cost design adapting the same for use as a "throw-away" unit thereby eliminating the necessity of maintenance.

Other objects not specifically set forth will become apparent from the following detailed description made in conjunction with the drawings wherein:

Fig. 1 is a vertical section of an improved refrigerant drier assembly incorporating the principles of the present invention, the block element forming a part thereof being partially sectioned;

Fig. 2 is a sectional view taken generally along line 2—2 of Fig. 1;

Fig. 3 is a perspective of the improved form of dehydrant block for use in the drier of the present invention;

Fig. 4 is a vertical section of an improved refrigerant drier cartridge, the block element forming a part thereof being partially sectioned; and

Fig. 5 is a vertical section of an improved refrigerant drier assembly utilizing the cartridge of Fig. 4.

In Figs. 1 and 2 an improved drier assembly is illustrated as being formed from a sleeve-like casing 10 of annular shape being closed at its ends by end closures 11 and 12 received thereabout. Each of the end closures 11 and 12 are identical in design and are each formed from a cap-like annular body portion 13 having a circumferentially continuous, axially extending flange 14 which is spun over the outer edge of an end of the casing 10 to fix the end closures 11 and 12 against displacement therefrom. Each of the end closures 11 and

2

12 has centrally located apertures which have received therein inlet and outlet nipples 15 and 16 which are provided with axially directed bores 17 for passing refrigerant through the drier, the outermost end portions of the nipples 16 being externally threaded at 18 to interconnect the drier within a refrigerant line.

The annular cap portion 13 of each end closure 11 and 12 is provided with a peripheral radially directed shoulder portion 19 formed integral with the flange portion 14.

10 The inner surface of the shoulder portion 19 of the end closure 11 clamps the peripheral edge portion of an annular screen disk 20 against the end of the casing 10 with which the end closure 11 is associated. The shoulder portion 19 of the end closure 12 clamps a screen disk 15 22 and an annular collar member 23 against the edge of the casing 10 associated therewith. The peripheral edge portion of the collar 23 which is clamped between the screen 22 and the end surface of the casing 10 is defined by a radially directed circumferentially continuous flange 24. As shown in Figs. 1 and 3, the inner edge of the annular flange 24 is formed integral with a frusto-conical portion 25 which in turn is integral with a centrally located, flat annular portion 26. The inner edge of the flat annular portion 26 is formed integral 20 25 with an axially directed annular sleeve portion 27 which is tightly received in wedged relation within an axially directed bore 28 of a molded dehydrant, block-like element 29. The flat annular portion 26 of the collar 23 engages an inner annular portion of a radial end surface 30 of the element 29 surrounding the outwardly opening end of the bore 28.

As particularly shown in Figs. 2 and 3, the outer longitudinally extending surface of the molded dehydrant block 29 is provided with a circumferentially continuous 35 series of axially extending, parallel, arcuate ribs 30 which provide a substantially increased surface area to the block 29 to provide for increased volume of refrigerant passing therethrough during the dehydration of the refrigerant. The central bore 28, as shown in Fig. 1, 40 terminates short of the free end of the block 29 within the casing 10. The free end of the block 29 is substantially spaced from the screen 20. Still further, the longitudinally extending outer surface of the block 28 defined by the ribs 30, is positioned within the casing 10 in spaced relation to the inner surface of the same.

45 To centrally position and support the block 29 within the casing 10, discrete particles 31 of dehydrant material are received within the casing 10 and completely fill up the space between the radial free end surface of the block 29 and the screen 20. Still further, the discrete particles 31 fill the space between the longitudinally extending outer ribbed surface of the block 29 and the inner surface of the casing 10. The positioning of the discrete particles 31 intermediate the outer surface of the block 29 and the inner surface of the casing 10.

50 The positioning of the discrete particles 31 intermediate the outer surface of the block 29 and the inner surface of the casing 10 allows these particles to centrally position and support the block 29 within the casing 10 thereby maintaining the spacing of the block 29 out of contact with the inner surface of the casing 10. The end of the block 29 to which the collar 23 is attached is supported by the collar by

55 reason of the peripheral flange portion 24 being clamped by the end closure 12 relative to the associated end of the casing 10. However, the remaining portion of the block 29 received within the casing 10, being of substantial mass, is supported and spaced away from the inner surface of the casing 10 by the positioning of the discrete particles of dehydrant material 31 about substantially the entire outer surface of the block 29. In this connection the groove-like portion defined by the outwardly expanded frusto-conical portion 25 of the collar 23 is 60 also filled with discrete particles 31 of dehydrant material.

70 In using the drier assembly of Figs. 1-3, refrigerant

flows through the bore 17 of the nipple 15 of the end closure 11, through the screen 20 and into contact with the substantial mass of dehydrant particles 31 positioned between the screen 20 and the particle-supported end of the block 29. The refrigerant is then free to flow inwardly through the particle-supported end of the block 29 into the central bore 28 thereof. Refrigerant is also free to flow in an axial direction along the outer surface of the block 29 and, in doing so, will contact a considerable surface area by reason of the provision of the arcuate ribs 30. At any point along the outer longitudinal surface of the block 29 the refrigerant may flow inwardly through the porous material forming the block 29 into the bore 28. Regardless of the direction of flow of any particular quantity of refrigerant, it will contact a substantial amount of desiccant or dehydrant particles 31 and will ultimately flow through a portion of the block 29 thereby being further contacted with dehydrating material. The dehydrated refrigerant will flow outwardly of the bore 28 through the sleeve 27, through the screen 22 and out of the drier through the bore 17 in the nipple 16 of the end closure 12.

It will be noted that regardless of the point at which a quantity of refrigerant enters the pores of the block 29 in flowing toward the bore 28, the distance which the refrigerant flows through the material of the block 29 is substantially the same. In this connection the innermost end of the bore 28 is spaced from the particle-supported end surface of the block 29 a distance approximately equal to the distance in a radial direction from the bore 28 to the outer longitudinal surface of the block 29. Consequently, a considerable active dehydrating area is provided by the particular construction of the block 29 and the manner in which it is positioned and held within the casing 10. Only a relatively small surface area of the block 29 is incapable of being contacted by the refrigerant being dehydrated and this area is that portion of the held end of the block 29 which is in engagement with the flat annular portion 26 of the collar 23. By providing the collar 23 with the frusto-conical portion 25, the outer peripheral end face portion of the block 29 is exposed to contact with refrigerant which flows the entire length of the block 29 into the groove-like portion defined by the expanding of the collar 23 away from the outer peripheral portion of the held end of the block 29. The increased refrigerant contact surface area provided by the fluted design of the block 29 and the manner in which the block is mounted within the casing 10 provides increased filter area permitting greater filter capacity. Still further, regardless of at which point a quantity of refrigerant enters the block 29, the distance which the quantity travels through the pores of the block before it reaches the bore 28 is substantially the same throughout the entire block. With these advantages the drier is capable of dehydrating a large quantity of refrigerant at a fast rate without the establishment of an excessive pressure drop. Any suitable type of desiccant material may be used in supplying the discrete particles 31 and the block 29. Material of this nature includes anhydrous calcium sulfate, activated alumina, silica gel, etc.

In Fig. 4 a cartridge type element incorporating the principles of the present invention is illustrated as being formed from a cylindrical casing member 33 of cylindrical shape being provided with outwardly expanded ring-like portions defining longitudinally and circumferentially spaced beads 34 for positioning the cartridge within a drier assembly as will subsequently be described. Received within one end of the casing 33 is the annular collar member 23 previously described, the radially directed continuous flange 24 of which is suitably fixed relative to the inner surface of the casing 33. The flange portion 24 may be force-fitted within the casing 33, soldered or attached in any suitable manner to the inner surface of the casing 33 so long as the collar 23 is fixed against movement relative to the casing 33. As pre-

viously described, the annular sleeve portion 27 is tightly received in wedged relation within the axially directed bore 28 of the molded dehydrant, block-like element 29. The flat annular portion 26 of the collar 23 engages the inner annular portion of the radial end surface of the block 29 surrounding the outwardly opening end of the bore 28.

The outer longitudinally extending surface of the block 29, being provided with the fluted portions 30, is positioned within the casing 33 in spaced relation to the inner surface of the same. Discrete particles 31 of dehydrant material are received within a casing 33 and completely fill up the space between the radial free end surface of the block 29 and a flanged perforated disk 35 telescopically received within an end of the casing 33. The perforated disk 35 functions in the same manner as the screen 20 described in connection with the drier assembly of Figs. 1-3. The outer periphery of the perforated disk 35 has integrally formed therewith an axially directed annular flange 36, the outer surface of which is suitably fixed relative to the inner surface of the casing 33.

The end of the casing 33 having received therein the collar 23 also receives a flanged disk-like screen 37 provided with an annular axially directed flange portion 38 which is fixed relative to the inner surface of the casing 33. A pull tab 39 is clamped between the flange portion 38 and the casing 33 and is freely available for grasping when it is desired to remove the cartridge from the outer casing or housing of a drier assembly of the type to be described in Fig. 5.

The cartridge of Fig. 4 is assembled by fixing the disk-like screen 37 with the pull tab 39 in place within one end of the casing 33 and inserting the combined block 29 and collar 23 within the casing 33. Upon proper positioning of the block 29 within the casing 33, the discrete particles 31 of dehydrant material are inserted to fill the space provided therefor about the block 29. The perforated flanged disk 35 is then inserted so as to cover the open end of the casing 33. The cartridge of Fig. 4 is a "throw-away" type adapted for use in a permanent type of drier assembly, one form of which is illustrated in Fig. 5.

The drier assembly of Fig. 5 includes a long outer casing or housing 41 of cylindrical shape being provided at one end thereof with an annular flange ring 42 fixedly attached to the outer surface thereof. The ring 42 is provided with a series of circumferentially spaced drilled apertures which are aligned with drilled apertures in the outer peripheral portion of a cover plate 43. A series of bolts 44 extend through the aligned apertures of the flange ring 42 and cover plate 43 and the latter is clamped to the end of the casing 41 by a series of nuts 45. A gasket 46 is received within an annular groove portion carried by the cover plate 43 and is clamped thereby in sealing engagement with the radial end surface of the casing 41 and the flange ring 42.

The inner surface of the cover plate 43 is provided with a flat annular shoulder portion 47 against which rests one end of a coil spring 48, the other end of which is in abutment with a radially directed portion of an annular collar 49 formed integral with a perforated cylinder 50 received within the spring 48. The collar 49 is further provided with an axially directed ring portion 51 which rides against the inner surface of the casing 41 and is movable relative thereto.

As illustrated in Fig. 5, an outlet fitting 52 is received through a portion of the casing 41 and suitably fixed thereto. Received within the casing 41 are two cartridge elements of the type described in Fig. 4. The cartridge elements are positioned in end-to-end relation with the disk-like screen 37 of the cartridge nearest the safety cylinder 50 opening into the interior of the safety cylinder 50. Intermediate the adjacent ends of the two cartridge elements is a spacer gasket 53 which is of resilient material to cushion any relative movement between the associated

cartridge elements and at the same time allow the cartridge elements to be tightly received within the casing 41. The beads 34 of the cartridge casings 33 position each cartridge with respect to the casing 41. The remaining end of the casing 41 has received thereabout an end cap 54 provided with an outer axially directed flange portion 55 which is suitably attached to the outer surface of the end portion of the casing 41. An annular gasket 56 is pressed between the inner surface of the end cap 54 and the outer portion of the screen 37 of the adjacent cartridge element. Thus, the end cap 54 tightly clamps the aligned cartridge elements within the casing 41 in fixed relation.

In the use of the drier assembly of Fig. 5, the end cap 54 is used as the inlet for the drier assembly with the refrigerant flowing from right to left as viewed. The refrigerant flows through the axially aligned cartridge elements and into the safety cylinder 50, through the perforations in the same and out of the casing 41 through the outlet fitting 52. The safety cylinder 50 functions to prevent discharge of broken or loose solid particles from the assembly in the event of rupture of any of the parts such as the adjacent screen 37. With the coil spring mounting of the same, the safety cylinder 50 resiliently holds the assembled cartridges in place.

The drier assemblies and cartridge element of the present invention are of uncomplicated construction and certain forms of the same are readily adapted for use as "throw-away" products thereby eliminating the necessity of regeneration with its accompanying maintenance costs. The drier assemblies and cartridge are readily assembled during the manufacture thereof and the discrete particles 31 of desiccant material not only function to dehydrate the refrigerant flow but further position and support a substantial portion of the dehydrant block 29 within the various casings. With this type of arrangement, the dual functioning of the discrete particles 31 results in the provision of an efficiently operating drier of low cost construction. The particular design of the dehydrant block 29 adapts the same for low cost manufacture by molding.

Obviously many modifications and variations of the invention as hereinbefore set forth may be made without departing from the spirit and scope thereof, and therefore only such limitations should be imposed as are indicated in the appended claims.

I claim:

1. A refrigerant drier comprising a sleeve-like casing having inlet and outlet closure members, a rigid porous dehydrant block of substantial relative length in said casing held at one end thereof in spaced relation to the inner surface of said casing by means fixed relative to said casing, and discrete dehydrant material within said casing and substantially surrounding said block, said discrete dehydrant material positioning and supporting the remainder of said block particularly the other end thereof within said casing in spaced relation to the inner surface of said casing.

2. The drier of claim 1 wherein said closure members are perforate screen-like members.

3. A refrigerant drier comprising a sleeve-like casing having inlet and outlet end closures, said end closures being in the form of caps received about the ends of said casing and each being provided with an axially directed nipple, a rigid porous dehydrant block of substantial relative length in said casing held at one end thereof in spaced relation to the inner surface of said casing by means fixed relative to said casing, and discrete dehydrant material within said casing and substantially surrounding said block, said discrete dehydrant material positioning and supporting the remainder of said block particularly the other end thereof within said casing in spaced relation to the inner surface of said casing.

4. A refrigerant drier comprising a sleeve-like casing having inlet and outlet closure members, a rigid porous dehydrant block in said casing held at one end thereof in

spaced relation to the inner surface of said casing by means fixed relative to said casing, said block extending axially within said casing from the end thereof holding the same to a point short of the remaining end of said casing, and discrete dehydrant material filling the remainder of said casing and substantially surrounding said block, said discrete dehydrant material positioning and supporting the remainder of said block particularly the other end thereof within said casing in spaced relation to the inner surface of said casing.

5. The drier of claim 4 wherein said closure members are perforate screen-like members.

6. A refrigerant drier comprising a sleeve-like casing having inlet and outlet end closures, a rigid porous dehydrant block of substantial relative length in said casing held at one end thereof in spaced relation to the inner surface of said casing by means fixed relative to said casing, said means being in the form of a collar having an axially directed sleeve received within an axially extending bore of said block, said collar being clamped between an end closure and said casing, and discrete dehydrant material within said casing and substantially surrounding said block, said discrete dehydrant material positioning and supporting the remainder of said block particularly the other end thereof within said casing in spaced relation to the inner surface of said casing.

7. A refrigerant drier comprising a sleeve-like casing having inlet and outlet closure members, a rigid porous dehydrant block of substantial relative length in said casing held at one end thereof in spaced relation to the inner surface of said casing by means fixed relative to said casing, said means being in the form of a collar having an axially directed sleeve received within an axially extending bore of said block, said collar being clamped between an end closure and said casing and having a circumferential peripheral portion thereof expanded away from the end face of said block to define a groove-like area exposing a portion of the end face of said block for contact with the refrigerant, and discrete dehydrant material within said casing and filling said groove-like area, said discrete dehydrant material positioning and supporting the remainder of said block particularly the other end thereof within said casing in spaced relation to the inner surface of said casing.

8. The drier of claim 7 wherein said closure members are perforate screen-like members.

9. A refrigerant drier comprising a sleeve-like casing having inlet and outlet end closures, a rigid porous dehydrant block of substantial relative length in said casing held at one end thereof in spaced relation to the inner surface of said casing by means fixed relative to said casing, a transversely positioned screen-like member at each end of said casing and clamped thereto by the associated end closure, and discrete dehydrant material within said casing substantially surrounding said block, said discrete dehydrant material positioning and supporting the remainder of said block particularly the other end thereof within said casing in spaced relation to the inner surface of said casing.

10. A refrigerant drier comprising a sleeve-like casing having inlet and outlet end closures, a rigid porous dehydrant block particularly the other end thereof in said casing held at one end thereof in spaced relation to the inner surface of said casing by means fixed relative to said casing, said means being in the form of a collar having an axially directed sleeve received within an axially extending bore of said block, said bore extending from the held end of said block and terminating short of the remaining end thereof, said collar being clamped between an end closure and said casing, the outer surface of said block being provided with a circumferentially continuous series of axially extending parallel arcuate ribs, and discrete dehydrant material within said casing and substantially surrounding said block, said discrete dehydrant material positioning and supporting the

75

remainder of said block within said casing in spaced relation to the inner surface of said casing.

11. A refrigerant drier cartridge comprising a sleeve-like casing having inlet and outlet perforate screen-like closure members, a rigid porous dehydrant block in said casing held at one end thereof in spaced relation to the inner surface of said casing by means fixed relative to said casing adjacent one of said closure members, said means being in the form of a collar having an axially directed sleeve received within an axially extending bore of said block, said bore extending from the held end of said block and terminating short to the remaining end thereof, said collar having a circumferential peripheral portion thereof expanded away from the end face of said block to define a groove-like area exposing a portion of the end face of said block for contact with refrigerant, the outer surface of said block being provided with a circumferentially continuous series of axially extending parallel arcuate ribs, said block extending axially within said casing from the end thereof holding the same to a point short of the remaining end of said casing as defined by the other of said closure members, and discrete dehydrant material within said casing and substantially surrounding said block, said discrete dehydrant material positioning and supporting the remainder of said block within said casing in spaced relation to the inner surface of said casing and further filling said groove-like area.

12. A refrigerant drier comprising a sleeve-like casing having inlet and outlet end closures, said end closures being in the form of caps received about the ends of said casing and each being provided with an axially

directed nipple, a transversely positioned screen at each end of said casing and clamped thereto by the associated end closure, a rigid porous dehydrant block in said casing held at one end thereof in spaced relation to the inner surface of said casing by means fixed to said casing, the outer surface of said block being provided with a circumferentially continuous series of axially extending parallel arcuate ribs, said block extending axially within said casing from the end thereof holding the same to a point short of the remaining end of said casing, and discrete dehydrant material within said casing and substantially surrounding said block, said discrete dehydrant material positioning and supporting the remainder of said block within said casing in spaced relation to the inner surface of said casing, said means being in the form of a collar having an axially directed sleeve received within an axially extending bore of said block, said bore extending from the held end of said block and terminating short of the remaining supported end thereof, said collar being clamped between an end closure and said casing and having a circumferential peripheral portion thereof expanded away from the end face of said block to define a groove-like area exposing a portion of the end face of said block for contact with refrigerant and receiving discrete dehydrant material therein.
